DESIGN FOR A PRESSURE COOKER

Everett R. Hamilton, Eau Claire, Wis., assignor to
National Pressure Cooker Company, Eau Claire,
Wis., a corporation of Wisconsin

Application October 10, 1938, Serial No. 80,354

Term of patent 7 years

To all whom it may concern:

Be it known that I, Everett R. Hamilton, a citizen of the United States, residing at Eau Claire, in the county of Eau Claire and State of Wisconsin, have invented a new, original, and ornamental Design for Pressure Cookers, of which the following is a specification, reference being had to the accompanying drawing, forming part thereof, and in which

Figure 1 is a perspective view of a pressure cooker, showing my new design; and

Figure 2 is a plan view of Figure 1.

I claim:

The ornamental design for a pressure cooker, as shown.

EVERETT R. HAMILTON.
